LOOM PICKER

Sherman D. Lesesne, Worcester, Mass., assignor
to Graton & Knight Company, Worcester,
Mass., a corporation of Massachusetts

Application March 27, 1946, Serial No. 657,531

3 Claims. (Cl. 139—159)

1

This invention relates to loom pickers and more particularly to the structure of the picker head which receives the shuttle and throws it in the reverse direction through the loom.

Pickers are customarily made of leather or of rubber cemented fabric; and many types of constructions have been tried to obtain a longer life and greater resistance to the impacts of the sharp nosed shuttle which gradually wears into the picker head and ultimately bursts it. Various attempts have also been made to reinforce the picker body by means of a surrounding metal casing; but so severe is the impact and bursting strain that in time the metal casing itself is ruptured. This necessitates stopping the loom and replacing the picker parts with a consequent loss of time for both the machine and the operator.

It is the primary object of this invention to provide a picker head construction having a metal reinforcement for the picker body, wherein the picker head is held resiliently but firmly on the picker stick and the shuttle receiving bore is so positioned as to give a long life of useful service. Other objects will be apparent in the following disclosure.

Referring to the drawings illustrating a preferred embodiment of the invention:

Fig. 1 is a vertical sectional view of the picker head mounted on the stick;

Fig. 2 is a front view of the head;

Fig. 3 is a rear view; and

Fig. 4 is an exploded view showing the assembly of the parts.

In accordance with this invention, I have provided a metal reinforced picker body made of several parallel impact disks, and preferably thick leather disks 10 and 11, carried in a reinforcing cup-shaped metal casing 12 having a peripheral cylindrical wall which substantially equalizes the radial stresses set up by the impact of the shuttle and an end wall 14 which receives the direct impact blow. A shuttle receiving bore or recess 15 is initially formed in the outer portion of the leather plug formed of the disks, and the plug is so positioned on the wooden picker stick 16 that the shuttle will fit accurately into this preformed bore at the initial blow.

The casing cup 12 is integral with and carried by a ferrule 18 which receives the top of the picker stick 16 and holds the head in a proper position. This ferrule is a hollow, open ended rectangular shell having a flat metal portion 19 provided with an outer face parallel with and secured in full contact with the outer face of wall 14, or the parts may be formed integrally. A leather strip or

2

facing 20 fits between the inside of the ferrule wall 19 and the side of the picker stick 16 and serves as a buffer. The parts are so arranged that the flat, parallel, cylindrical impact disks 10 and 11 are mounted on the flat end wall 14 of the cup-shaped casing 12, and the impact blow is transmitted substantially perpendicularly and directly from the bottom disk to the wall 14 and thence to the metal wall 19 of the rectangular ferrule. The picker head is shaped to be tilted down through a small angle, such as 6 degrees, relative to the center line of the stick, as is indicated by the wedge shape of the wall 14.

As shown in the exploded view of Fig. 4, the ferrule 18 may be made of sheet steel bent to form a hollow body of substantially rectangular cross section, with the rear wall 21 formed of two overlapping layers welded together. The ferrule is cut away to provide a beveled edge 22 which permits the head to clear a buffer strap mounted on the loom frame. The steel casing 12 may be suitably formed, as by a drawing and punching operation, to provide a cup for holding the leather impact disks. The cup has two parallel spaced ears 23 which fit tightly against the opposite parallel sides of the ferrule when assembled. The ears may be secured to the ferrule by a silver solder or by a brazing or welding operation, so as to provide an integral structure having the walls 14 and 19 in contact. The walls 14 and 19 may be resistance welded together and the ears 23 omitted, but the latter serve a useful purpose in that they are tapered and merge into the wall of the ferrule and prevent a thread from catching 35 on the picker head.

The picker head, comprising the metal casing 12 and the ferrule 18, is held firmly in position on the picker stick 16 by means of the leather strip 20 and a resilient rubber body 24, or buffer located between the picker stick 16 and the rear wall 21 of the ferrule. The buffer 24 is placed under compression when the picker head is driven onto the stick. The picker stick tapers slightly upwardly and the parts are shaped to provide a wedging effect. The rubber layer 24 keeps the parts in tight engagement at all times and it, in particular, protects the stick from being chewed up by the ferrule and thus prevents looseness from developing. The ferrule has an elongated 50 slot 26 through which a tapered wood screw 27 is screwed into the stick after the picker body has been properly located on the stick and thus prevents the body from moving up or down relative to the shuttle nose. This screw, however, is 55 not intended to secure the parts together and

keep the picker from wobbling on the stick. In fact, the slot 24 is made elongated so that any horizontal motion of the picker head under the impact blows will not wear or cut the screw. That is, this screw is solely for the purpose of locating the picker body vertically and it does not serve to connect the picker head rigidly to the stick; and the elongated slot cannot resist any slight longitudinal movement of the picker head as is permitted by the resilient rubber body 24.

The elastic rubber buffer 24 serves an important function. It is made of resilient rubber of low compression set, and it preferably has that composition which, when squeezed to one-half of its thickness, will return substantially to its original shape and thickness when the compression stress is released and even after a long period of compression. The preferred rubber composition is made in accordance with standard practice of vulcanized rubber which has a durometer hardness of about 72%. This rubber, when squeezed with a deflection or compression of 30% for three days at 160° F., will have a compression set of 80%. When the head is driven onto the picker stick, the buffer is compressed about one half, but under normal temperature and impact conditions, it will return to substantially its original thickness after the pressure has been released. Thus, this rubber buffer serves as an elastic, resilient body which keeps the picker head firmly positioned on the stick and yet provides a resilient buffer that absorbs the shock incident to the sudden forward movement of the picker stick in returning the shuttle. So important is this rubber buffer that, if it were omitted, the life of the picker head would be decreased materially.

Leather differs in its structure, and its stretch and tensile stretch depend upon the source of the hide and its treatment, as well as the location where the piece is cut from the hide. Hence I choose for the impact members 10 and 11 the thicker portions of an oak tanned leather hide or a hide treated by other satisfactory tanning methods; and I preferably employ leather for the leather disk 10 which is about one quarter of an inch or more in thickness and not less than $\frac{1}{16}$ " thick. The inner layers 11 may be thinner, but I prefer that they be as thick as the layer 10. The flesh side of the leather is tougher and more resistant to the impact of the pointed shuttle than is the grain or skin side of the leather, and for this reason I place the leather layers, or at least the outer layer 10, with their flesh sides facing outwardly toward the shuttle.

The leather disks 10 and 11 are cemented together to form a solid leather plug, and the plug itself is cemented into the cylindrical casing 12 so as to prevent movement of the leather parts relative to each other and to the casing. The preferred leather cement is a flexible cement, such as an animal or hide glue or a suitable rubber cement, so that the parts will be held together under the impact blows of the shuttle and the cement will not break down. Likewise, the impact layer of leather 20 is made of a strong piece of leather and preferably of oak tanned hide. That leather serves to insulate the metal from the wood stick 16 and prevent the metal body from wearing or chewing into the stick. The leather strip 20 is cemented to the inner wall face 19 of the ferrule. This leather has a high friction coefficient and prevents the picker from slipping on the stick, and its slight compressibility is such that when the picker head is driven 75 metal casing having its closed end integral with

onto the stick with sufficient force to compress the back rubber layer 24 to one half of its thickness, the leather body is likewise compacted slightly to a very firm condition and thus holds the parts very tightly assembled.

Although the impact body is preferably made of leather, I may for certain purposes employ layers of strong textile fabric of cotton, rayon or nylon, and preferably coarse cotton fabric of the 10 type of heavy duck or canvas, which are cemented together by vulcanized rubber. The layers of fabric are substantially in contact but the rubber coats their surfaces and unites them into a resilient but substantially integral body. This rubber plug is likewise cemented into the metal ferrule with rubber cement.

The various types of pickers have been tested on an accelerated testing machine, a machine having a sliding member mounted on slide rods 20 and carrying an impact body shaped like a shuttle nose which is reciprocated by a cam at a fixed rate. Each type of picker was tested seven times to disruption. The average life for the seven all-leather pickers, which were not metal reinforced, was 92,000 blows before the leather picker burst. A rawhide picker under similar treatment averaged 180,000 blows before disruption. A rubber cemented fabric picker without metal reinforcement averaged 408,000 blows; 30 while a picker made in accordance with this invention of rawhide leather discs cemented together and reinforced by the steel casing and held in place by the leather and rubber buffers withstood 2,200,000 blows on the average, and some of 35 the pickers stood up for 3,000,000 blows.

It was also found that the initial location of the shuttle receiving bore 15 above the center line of the cylindrical casing 12 added very materially to the life of the picker. That initial pilot bore is preferably located $\frac{3}{16}$ " above the center line of the plug. The picker is so located on the stick that the shuttle nose initially fits accurately into the bore. Then as time goes on, the shuttle tends to wear the recess in the leather body 45 downwardly or towards a concentric position, until it is substantially centered within the cylindrical casing near the end of its useful life and thus causes the impact stresses to be distributed substantially uniformly in a radial direction at a time when these blows tend to provide a greater strain on the reinforcing casing.

The operation of the device will be apparent to one skilled in the art, in view of the above disclosure. The utility and the primary constructional features have also been explained. It, however, may be noted that the ferrule should be longer transversely than the thickness of the picker stick and that the space thus provided be filled by the leather and rubber buffers, which 55 are so thick that the rubber must be compressed to a materially smaller dimension so as to insure a tight fit of the head on the stick. I prefer that the rubber buffer be at least $\frac{1}{8}$ " and preferably $\frac{1}{16}$ " thick. It is also desirable that the impact plug be formed of parallel layers of material located in a cylindrical metal casing so that the bursting stresses will be properly distributed. Other aspects of this construction have been set forth above. It will now be appreciated that various modifications may be made in the constructional details of this device within the scope of the appended claims.

I claim:

1. A loom picker head comprising a cup shaped

a metal ferrule whose opening is longer transversely than the corresponding dimension of the picker stick which is surrounded thereby, a layer of resilient material on the inner wall of the ferrule remote from the base of the casing which is highly compressed by insertion of the stick into the ferrule and serves to hold the head tightly on the stick without wearing the latter, a resilient buffer between the base of the casing and the adjacent face of the stick, means for locating the head on the stick and limiting its movement lengthwise thereof but which does not restrict transverse movement provided by the resilient material, and impact receiving means secured within the casing for receiving the impact of the shuttle.

2. A loom picker head comprising, a metal ferrule having a forward and a rear wall, a cup-shaped metal casing formed integrally with the forward wall of the ferrule, a resilient buffer on the inner surface of each of said walls, the spacing between said buffers being less than the corresponding dimension of a picker stick on which said head is adapted to be used, and an impact absorbing member in said cup whereby impacts are transmitted to the picker stick solely through said buffers, said forward and rear walls being joined by side walls, at least one of which has a fore and aft elongated opening therein adapted to receive a retaining pin on the stick whereby to locate the head on the stick and limit its movement lengthwise thereof but not limiting transverse movement provided by the resilient buffers.

3. A loom picker head comprising, a metal ferrule having a forward and a rear wall, a cup-shaped metal casing formed integrally with the forward wall of the ferrule, a resilient buffer on the inner surface of each of said walls, the spacing between said buffers being less than the corresponding dimension of a picker stick on which said head is adapted to be used, and an impact absorbing member in said cup whereby impacts are transmitted to the picker stick solely through said buffers, one of said buffers being more readily compressible than the other, said forward and rear walls being joined by side walls, at least one of which has a fore and aft elongated opening therein adapted to receive a retaining pin on the stick whereby to locate the head on the stick and limit its movement lengthwise thereof but not limiting transverse movement provided by the resilient buffers.
